Inc., Providence, R.I., a corporation of Rhode Island

Filed Mar. 28, 1966, Ser. No. 1,651

Term of patent 14 years

(Cl. D45—4)

FIG. 1

FIG. 2

FIG. 3

FIG. 4

FIG. 6

FIG. 5

FIG. 1 is a top plan view of an expansible link chain for a bracelet embodying my new design with the links in contracted position;

FIG. 2 is a view similar to FIG. 1 with the links in an expanded position, portions of the conventional appearing bottom links being visible between the expanded top links;

FIG. 3 is an enlarged top plan view of a single top link of the expansible chain; and

FIG. 4 is an edge elevational view looking from right to left at the top link shown in FIG. 3;

FIG. 5 is an enlarged perspective view of the top link shown in FIG. 3; and

FIG. 6 is a cross-section taken on the line 6—6 of FIG. 3 and following the bottom of the groove.

The essential features of my design reside in the portions shown in full lines.

I claim:

The ornamental design for an expansible link chain for a bracelet or similar article, substantially as shown and described.
